UNITED STATES PATENT OFFICE.

EDWIN O. BENTLEY, OF BENTLEY SPRINGS, MARYLAND, ASSIGNOR OF ONE-HALF TO CHARLES W. BENTLEY, JR., OF SAME PLACE.

DESIGN FOR A PUZZLE-BOARD.

SPECIFICATION forming part of Design No. 26,010, dated September 8, 1896.

Application filed August 5, 1896. Serial No. 601,812. Term of patent 7 years.

To all whom it may concern:

Be it known that I, EDWIN O. BENTLEY, a citizen of the United States, residing at Bentley Springs, in the county of Baltimore and State of Maryland, have invented a certain new and original Design for Puzzle-Boards, of which the following is a specification, reference being had therein to the accompanying drawings.

10 In the drawings annexed, Figure 1 is a plan view, and Fig. 2 a transverse section, of the design.

Referring to the drawings by letter, *i* designates a rectangular channel in the face of the board and having its four sides substantially parallel with the four edges of the board and having inclosed within it and connected to it a series of connected channels, arranged as follows: A vertical channel *a* is arranged parallel to the left side of the continuous channel *i*, and a similar channel *h* is located near the right side of that channel. Connected to the channel *a* by a cross-channel *b* is a scroll-like channel *c*, which is approximately the same height as the channels *a* and *h*, and which has its upper and lower portion connected, respectively, to the upper and lower parts of the channel *i* by means of

short straight channels *j*. Connected to the channel *c* by a cross-channel *d*, and partly inclosed within said channel, is a T-shaped channel *e*, and connected to the vertical part of this latter channel by a cross-channel *f* is an oval channel *g*, this latter channel lying between the channel *c* and the channel *h* and being connected to the latter by a short cross-channel *g'*, and the channel *h* being in turn connected by a short cross-channel *l* to the right side of the channel *i*.

It will be observed that the upper part of the scroll-like channel *c* curves over toward the right and slightly downward toward the upper cross-bar of the channel *e*, and that the lower part of the channel *c* curves first under toward the right and then upward and inward and slightly downward, forming a sort of curl.

What I claim is—

The design for a puzzle-board, substantially as herein shown and described.

In testimony whereof I affix my signature in presence of two witnesses.

EDWIN O. BENTLEY.
